[57] CLAIM

The ornamental design for a flexible trash bag for a vehicle, as shown and described.

DESCRIPTION

FIG. 1 is a front elevation view of the flexible trash bag for a vehicle showing my new design;

FIG. 2 is a rear elevation view of the flexible trash bag for a vehicle shown in FIG. 1;

FIG. 3 is a right elevation view of the flexible trash bag for a vehicle shown in FIG. 1;

FIG. 4 is a left elevation view of the flexible trash bag for a vehicle shown in FIG. 1;

FIG. 5 is a top plan view of the flexible trash bag for a vehicle shown in FIG. 1;

FIG. 6 is a bottom plan view of the flexible trash bag for a vehicle shown in FIG. 1; and,

FIG. 7 is a rear perspective view of the flexible trash bag of claim 1 shown with a lower wend in an open position.

The surface(s) or portion(s) of the article not shown in the drawing or described in the specification form(s) no part of the claimed design.
